METAL BEAM

Donald Albert Palmer, Cardiff, Wales

Application December 30, 1948, Serial No. 150,445
In Great Britain January 2, 1948

Term of patent 14 years

(Cl. D54—1)

To all whom it may concern:

Be it known that I, Donald Albert Palmer, a citizen of the United Kingdom, residing at Pen-gam Road, Roath, Cardiff, in the county of Glamorgan, Wales, have invented a new, original, and ornamental Design for a Metal Beam, of which the following is a specification, reference being had to the accompanying drawing, forming part thereof, in which

Figure 1 is a side elevation of a metal beam, embodying my new design.

Figure 2 is an end elevation of the beam depicted in Figure 1.

Figure 3 is a sectional view on the line 3—3 of Figure 1.

I claim:

The ornamental design for a metal beam, as shown.

DONALD ALBERT PALMER.
